LIGHTER

John A. Hanley, Stamford, Conn.

Application June 30, 1933, Serial No. 678,365

4 Claims. (Cl. 67—7)

This invention relates to a lighter of the flameless type. The lighter includes a block or disk of platinized material which glows under a heat caused by the influence of vapor of methyl alcohol or similar fluid. The catalytic action of the vapor on the disk of material used for lighting is only desired when the device is to be used in lighting.

In this particular form of lighter the lighting disc is shielded from the vapor. This is economical and also makes for a more perfect performance in that it prevents condensation on the disk which condensation takes place when the disk is constantly in the presence of the vapor. Such condensation from the vapor saturates the disk and prevents the operation of the lighter.

The object of this invention is to provide a lighter in which the disk or element is completely shielded from any contact with the vapor unless the user operates the lighter to allow such contact. This makes the lighter effective.

Another object of the invention is to allow for adequate admission of air to the body of the lighter when the disk is in the presence of the vapor and to shut off the air when the disk is shielded from the vapor.

A still further object is to provide a means for ventilating the disk when it is not in use for lighting in order to prevent condensation.

The invention also consists in certain details of construction which will be described in detail hereinafter and also embodied in some of the claims.

The invention is illustrated in the accompanying drawing. Figure 1 is a longitudinal section of a lighter embodying my invention. Figure 2 is a similar view of the top part of the lighter with the ignition disk in lighting position. Figure 3 is a top view of the lighter shown in Figure 1. Figure 4 is a central cross-section of Figure 1. Figure 5 is an end view of the lighter shown in Figure 1. Figure 6 is a top view and Figure 7 is a central section of a lighter of modified form. Figure 8 is an end view of the lighter shown in Figure 7.

The lighter comprises a casing 10 usually made of sheet metal which contains a mass 11 of felt, cotton or other suitable absorbent which is saturated with a liquid such as methyl alcohol which supplies a vapor that will cause, by catalytic action, a glow and a heating up of a mass of platinized material such as platinum sponge.

The top of the casing is provided with a means for holding such disk or body of platinized material and with means for controlling the contact

and/or shielding of the disk with or from the vapor. The piece of material to be heated is carried on a holder and the casing is provided with a part into which the material can be moved when not used for lighting purposes. In the form shown I move the disk in or out of position for lighting and contact. The disk is shown at 12 and it is placed in a slide 13 which has a suitable finger piece 14 for operating the slide. The slide is placed in a slideway formed between the top 15 of the casing and the horizontal partition 16 in the casing. The slide fits snugly in the space between the top and partition and can thus be isolated when not in use. The top and partition are provided with aligned holes 17 and 18 with which the disk 12 can be placed in register when it is to be heated and used for lighting. A cigarette can be placed against the outer face of the disk through the hole 17.

The hole 18 allows vapor to contact with a disk 75 that is over it. A screen 19 is preferably used forming a vapor chamber 20.

The drawing in Figure 1 shows the slide in what I will call the inoperative position, that is, with the disk 12 shielded from vapor and in Figure 2 80 the disk is shown in what I term its operative position ready for lighting.

The casing 10 and the slide 13 may have co-operative means for holding the slide in its two positions. I show the spring lip 21 with a projection 22 on its under side and two notches 23 and 24 to receive the projection to maintain the slide in either of its two positions.

The top 15 has a ventilation opening 25 in it. This is placed at a point where it will be above 90 the disk 12 when the slide is in inoperative position. This allows the vapor to pass out of the disk 12 to prevent condensation and thus keep the disk 12 dry.

Air openings are provided to allow air to enter 95 the casing and the filling 11. These openings are uncovered when the disk is in contact with the vapor and are closed when the disk is covered. The construction shown employs the slide as a control means for the admission of air through these openings. The air openings 27 and 28 are preferably at the end of the cover or top 15 and the partition 16, respectively. They are shown as closed in Figure 1 and uncovered in Figure 2.

It will be evident that when the lighter is not 105 in use the slide 13 is slid in to its inoperative position thus closing the air openings 27 and 28, placing the disk 12 under the ventilation opening 25, and closing the holes 17 and 18 to confine vapor to the casing below the partition 16.

When the lighter is to be used the slide is pulled out until the disk 12 is over the hole 18 and the vapor contacts with the disk 12 and heats it. A cigarette can then be lighted by placing it against

- 5 the disk 12 through the hole 17. At the same time the slide 15 uncovers the air openings 27 and 28 which permits air to enter the casing and facilitate the passage of vapor from the filling to the disk 12. This will be clearly seen from Figure 2.
- 10 A modified form is shown in Figures 6 to 8. This structure is, in general, the same comprising the casing 10, the filling 11, the cover 15 and the partition 16. There is, in addition, a plate 29 spaced from the partition 16 to form a vapor chamber 30. The plate 29 has perforations 31 in it. The slide is modified and is shown at 32 with the finger piece 33 arranged with its neck 34 sliding in a slot 35. This form is compact in that the slide at no time projects beyond the dimensions of the casing.
- 15 The top 15 may be part of a separate cover 36 with indentations 37 which snap into indentations 38 in the casing to form a tight closure. This allows access to the slide for repair and facilitates installation of the disk 12.

The disk 12 may be provided with a beveled circumference fitting into undercut edges 39 of the hole in the slide provided for the reception of the disk. The slide is preferably made of material of low heat conductivity for holding the disk 12.

Various changes can be made in the form and dimensions of the various parts without departing from the scope of my invention.

- 35 I claim:
1. A lighter comprising a casing having an opening for the outlet of fuel vapor, a piece of catalytic material, a holder for the piece of material, the casing having a recess to receive the material, said holder being movable to alternately place the material over the outlet or in the recess.

- 45 2. A lighter comprising a casing having an opening for the outlet of fuel vapor, a piece of catalytic material, a holder for the piece of material, the casing having a recess to receive the material, said holder being movable to alternately place the material over the outlet or in the recess, the recess being provided with a cover which is movable to cover the recess when the material is over the outlet and to uncover the recess when the material is over the outlet.

- 50 3. A lighter comprising a casing having an opening for the outlet of fuel vapor, a piece of catalytic material, a holder for the piece of material, the casing having a recess to receive the material, said holder being movable to alternately place the material over the outlet or in the recess, the recess being provided with a cover which is movable to cover the recess when the material is over the outlet and to uncover the recess when the material is over the outlet.

- 55 4. A lighter comprising a casing having an opening for the outlet of fuel vapor, a piece of catalytic material, a holder for the piece of material, the casing having a recess to receive the material, said holder being movable to alternately place the material over the outlet or in the recess, the recess being provided with a cover which is movable to cover the recess when the material is over the outlet and to uncover the recess when the material is over the outlet.

- 60 5. A lighter comprising a casing having an opening for the outlet of fuel vapor, a piece of catalytic material, a holder for the piece of material, the casing having a recess to receive the material, said holder being movable to alternately place the material over the outlet or in the recess, the recess being provided with a cover which is movable to cover the recess when the material is over the outlet and to uncover the recess when the material is over the outlet.

- 65 6. A lighter comprising a casing having an opening for the outlet of fuel vapor, a piece of catalytic material, a holder for the piece of material, the casing having a recess to receive the material, said holder being movable to alternately place the material over the outlet or in the recess, the recess being provided with a cover which is movable to cover the recess when the material is over the outlet and to uncover the recess when the material is over the outlet.

- 70 7. A lighter comprising a casing having an opening for the outlet of fuel vapor, a piece of catalytic material, a holder for the piece of material, the casing having a recess to receive the material, said holder being movable to alternately place the material over the outlet or in the recess, the recess being provided with a cover which is movable to cover the recess when the material is over the outlet and to uncover the recess when the material is over the outlet.

- 75 8. A lighter comprising a casing having an opening for the outlet of fuel vapor, a piece of catalytic material, a holder for the piece of material, the casing having a recess to receive the material, said holder being movable to alternately place the material over the outlet or in the recess, the recess being provided with a cover which is movable to cover the recess when the material is over the outlet and to uncover the recess when the material is over the outlet.

cess, the holder also having a part to cover the outlet when the material is in the recess, the casing having an air inlet placed to be closed by the holder when the material is in the recess.

- 90 2. A lighter comprising a casing having a hole therein for the passage of fuel vapor, a slide-way in the top of the casing, a slide movable in the slide-way and extending across the hole and a piece of catalytic material for lighting purposes in the slide and arranged to be placed over the hole when the slide is in operative position, the casing having an air inlet arranged in a position that will cause it to be uncovered by the slide when in operative position and to be covered by the slide when in inoperative position.

- 95 3. A lighter comprising a casing having a top and a partition spaced from the top to form a slide-way, a slide fitting in the slide-way and containing a piece of catalytic material for ignition purposes, the top and partition having holes for providing a fuel vapor outlet over which the slide extends whereby the material can be alternatively placed in the outlet or shielded in the slideway, the top having a ventilation opening placed where the material is located when it is shielded.

- 100 4. A lighter comprising a casing having a top and a partition spaced from the top to form a slide-way, a slide fitting in the slide-way and containing a piece of catalytic material for ignition purposes, the top and partition having holes for providing a fuel vapor outlet over which the slide extends whereby the material can be alternatively placed in the outlet or shielded in the slide-way, the top having a ventilation opening placed where the material is located when it is shielded, the top and partition having air inlet openings located in a position to be closed by the slide when the material is shielded and opened when the material is over the outlet.
